UNITED STATES PATENT OFFICE.

MAURICE J. WOHL, OF NEW YORK, N. Y., ASSIGNOR TO ECONOMY ELECTRIC COMPANY, A CORPORATION OF NEW YORK.

DESIGN FOR A WATCH-CHARM OR SIMILAR ARTICLE.

No. 39,616.

Specification for Design.

Patented Oct. 13, 1908.

Application filed June 16, 1908. Serial No. 438,867. Term of patent 14 years.

To all whom it may concern:

Be it known that I, MAURICE J. WOHL, a citizen of the United States, and resident of the city, county, and State of New York, have invented a new, original, and ornamental Design for a Watch-Charm or Similar Article, of which the following is a specification, reference being had to the accompanying drawing, forming part thereof.

Figure 1 is a front elevation of a device, showing my new design. Fig. 2 is a side elevation of Fig. 1.

The design comprises a flat member hav-

ing a contracted central portion, when viewed in front elevation, and provided with enlarged upper and lower portions of ornamental outline, as shown in Fig. 1. The lower end terminates in an acorn shaped portion in outline.

I claim:

The ornamental design for a watch charm, or similar article, as shown and described.

MAURICE J. WOHL.
